(57) **CLAIM**

The ornamental design of a medical device case, as shown and described.

DESCRIPTION

FIG. 1 is a perspective view of a medical device case embodying the design of the present invention;
FIG. 2 is a front elevation view of the medical device case illustrated in FIG. 1;
FIG. 3 is a rear elevation view of the medical device case illustrated in FIG. 1;
FIG. 4 is a right side elevation view of the medical device case illustrated in FIG. 1;
FIG. 5 is a left side elevation view of the medical device case illustrated in FIG. 1;
FIG. 6 is a bottom view of the medical device case illustrated in FIG. 1; and,
FIG. 7 is a top view of the medical device case illustrated in FIG. 1.

1 Claim, 7 Drawing Sheets
